UNITED STATES PATENT OFFICE.

HENRY FAKE, OF CHICAGO, ILLINOIS, ASSIGNOR OF FOUR-FIFTHS TO ELMIRA FAKE, WARREN S. FAKE, GEORGIANA FAKE, AND JOSEPHINE E. FAKE FLEETWOOD, ALL OF SAME PLACE, ONE-FIFTH TO EACH.

WATER-WHEEL.

SPECIFICATION forming part of Letters Patent No. 240,820, dated May 3, 1881.

Application filed December 27, 1880. (Model.)

To all whom it may concern:

Be it known that I, HENRY FAKE, a citizen of the United States, residing at Chicago, in the county of Cook and State of Illinois, have 5 invented certain new and useful Improvements in Current and Tide-Water Wheels, of which the following is a specification.

My invention relates more particularly to improvements upon my current and tide-water wheel patented November 16, 1880, No. 234,396; and the main objects of my improvements are, first, the strengthening of the main rim of the wheel and the fastening of the braces, so as to increase their efficiency and to 10 admit of the adjustment of the wheel whenever the same varies from a horizontal position; second, the making of the buckets or blades concave, so as to exert greater power from the same volume of water; third, having that portion 15 of the buckets extending above the radial arms and the weights that act upon the same of such a construction as not to resist the current of the stream, and to admit of the working of the wheel when submerged; fourth, so 20 constructing the water-way or race that the current will move in the same direction as the motion of the wheel, thus causing the force of the water to strike the buckets or blades very nearly direct, and not at a considerable angle, 25 so as to increase the power of the wheel; fifth, the placing of a wedge-shaped structure in the water-way or race at a suitable distance from the wheel, so as to separate the current and cause 30 it to pass along the sides of the race, thus increasing both the volume and velocity of the water at its most direct points of contact with the buckets, and causing the water to strike the buckets at the point where its utmost force 35 will be utilized; sixth, the use of pulleys in the place of guide-eyes and chains in the place of cords, as a part of the mechanism by which I operate the bucket-weights, as the guide-eyes mentioned in my former patent cause too 40 much friction, while cords do not have the required degree of strength and durability, and wire rope is not sufficiently pliable to admit of a free action of the weights. The foregoing improvements add to the strength of my im- 45 proved current and tide-water wheel and re-

sult in greater efficiency in its operation in slight currents, my wheel being the only one to my knowledge which is so constructed as to prevent any waste of water, the buckets being so fitted to the water-way that the water cannot escape without coming in contact therewith. I attain these objects by the improved mechanism illustrated in the accompanying drawings, in which—

Figure 1 is an elevation with the water-way 60 in cross-sections. Fig. 2 is an elevation with the water-way and the bearings for the wheel in cross-section, and all but one of the paddles and weights removed. Fig. 3 shows the race or water-way, together with the wedge-shaped 65 structure constructed therein. Fig. 4 is perspective view of one of the buckets.

Similar letters refer to similar parts throughout the several views.

On the drawings, A indicates the outer or 70 main rim of the wheel; B and C, two sections of the wheel. B' indicates one of the supporting-sections; D, a secondary rim or band; E, a circular plate or small hub; F, the shaft; G, the hub; H, the radial arms of the wheel; I, 75 braces or supports; J, the nuts which secure the braces; a, chains for operating the bucket-weights; b, pulleys through which the chains pass; c, a link-rod or chain for operating the adjusting-chains; d, a swivel-coupling; e, a 80 chain leading to the windlass; f, weights; h, buckets or blades; g, the bolts with nuts or bands, by which the buckets are connected with the radial arms and rim of the wheel; k, the strengthening-chains connecting the buckets to 85 the radial arms; W, the water-way or race; X X', the walls of the race, X' being the curved wall, which shows the direction of the current where it comes in contact with the buckets or blades; Z, the wedge-shaped structure erected 90 in the middle of the race or water-way.

The device as a whole is supported by a suitable frame-work, which will vary in form, as set forth in my former patent.

The rim of the main wheel A is made in two 95 or more sections, according to the size. These sections are mortised and tenoned where they are joined together. B and C indicate the two sections shown in the drawings.

For the purpose of strengthening the rim of 100

the main wheel, I place upper strengthening-sections, B', these sections, forming the upper rim of the wheel, being so placed as to break joints with the sections of the lower rim of the 5 main wheel, and are fastened by strong screws or by bolts passing through the main rim and secured by nuts on the under side.

The braces or supports I, I either attach to the circular plate or small hub E by having 10 them so bent at the upper end as to hook into this circular plate, or by having the braces pass up through the plate and secured by nuts. I attach the lower end of the braces by passing them through the main rim of the wheel 15 and the upper supporting-sections and securing them on the under side by the nuts J, as this method permits me to adjust the wheel in case it does not run true. The braces should pass through the rim at the several points of 20 intersection by the radial arms, so as to answer the double purpose of supporting the wheel and holding the arms in place.

I make the secondary rim or band D of two or more sections, and secure the same to the 25 braces by screw-staples, which pass around the braces and are fastened at the outer ends by nuts.

Any kind of chain that will work freely over pulleys can be used to operate the bucket- 30 weights, and the pulleys b can be fastened in any suitable manner to the secondary rim or band D; or they may be fastened direct to the braces. The pulleys in number want to correspond with the size of the wheel, but never 35 less than three are to be used.

The chains a, by which I operate the weights, are connected with and operated by the link-rod or chain, which passes through an open gudgeon inserted into the upper end of the 40 shaft F, said link-rod or chain being used in connection with the swivel-coupling d to prevent the rotation of the wheel from twisting the chains.

I construct my improved weights f of wood, 45 iron, or other suitable material, and make them skeleton instead of solid. I also make the upper part of the buckets or blades h skeleton, my object in both instances being to avoid as much as possible the resistance of the water, 50 and to permit the wheel to operate when submerged by high water. These weights may be made of any desired size or weight required to operate the buckets, and may be pivoted to the radial arms of the wheel, or fastened by 55 bolts passing through the arms and secured by nuts or by iron bands passing around the arms.

My improved buckets or blades I make concave below the point where they are pivoted to the radial arms, so as to secure additional 60 surface for the water to come in contact with and increased power, both from the force and weight of the water. These buckets may be constructed of wood or any suitable metal; may be of any size or depth that the dimensions of the wheel and the power required may 65 demand.

The lower portion of the side or outer edge of my buckets or blades is made on an angle, so as to admit of their free action when thrown out of the water by their weights; as it will 70 be readily seen that, pivoted to or connected with the radial arms of a circular wheel, the buckets would, if the outer edge were straight, come in contact with the rim of the main wheel when thrown out of the water.

I construct the outer end of my race at such an angle at the side as to correspond with the angle of the buckets, and thus prevent the escape of a portion of the water without first 75 flowing against the buckets.

I prefer to fasten the buckets or blades to the radial arms and main rim of the wheel by means of bolts passing through the arms and rim and held in place by nuts; but it is evident that they may be fastened by bands passing around the arms, or in any other suitable manner. To prevent my improved buckets from being carried away or broken by the action of the water, I connect them by chains, from a point near the lower part, to the radial 80 arm next in the rear of the one to which they are attached.

I construct my improved race or water-way so that the side or wall X' is curved for some 85 distance back from the point where the water first comes in contact with the buckets. The curvature of the wall X' should be such as to cause the current of water on that side of the race to strike the buckets in the direction of the motion of the wheel, and not at any considerable angle, thus utilizing to the utmost 90 the force of the water.

To increase the current and volume of water at the sides of the water-way or race, I build a wedge-shaped structure, Z, in the race at a 105 suitable point between the gate and wheel, the pointed end of the structure being in the opposite direction from the wheel. This structure can be of timber or stone, and may be of a height to correspond with the walls of the 110 water-way. I prefer to erect the same in the center of the race or at equal distance from the sides. The sides of this structure may be placed at any suitable angle; but I prefer to place them at an angle of forty-five degrees, 115 and to have the structure of such width as to extend at the widest part half-way across the race, leaving at the narrowest point a channel 120 on each side of one-quarter of the width of the race. By thus erecting this structure I divide 120 the water, and both turn the volume and increase the force of the current at the sides, where it most readily comes in contact with the buckets and is most available in giving power to the wheel, thus greatly increasing its 125 efficiency both in slight currents and low water.

What I claim as new, and desire to secure by Letters Patent, is—

1. The combination of the main rim of the 130 wheel A, the strengthening-sections B', and the circular plate or small hub E, connected

by supports or-braces I, secured and operated by the nuts J, substantially as specified.

2. The concave buckets h, having a skeleton extension above the point where they are hinged, in combination with the skeleton weight f, acting upon the bucket-extensions, substantially as described.

3. The chains a and e, the link-rod or chain c, and pulleys b, in combination with the weights f and buckets h, substantially as set forth.

4. The concave buckets h, strengthening-chains k, and bolts with nuts or bands g, in com-

bination with the arms H, rim A, and weights f, substantially as described.

5. The water-way or race W, having the 15 curved wall X', in combination with the wedge-shaped guide Z, for directing the current of water, substantially for the purpose set forth and described.

HENRY FAKE.
